INSTANTANEOUS WATER-HEATER.

1,223,653.

Specification of Letters Patent. Patented Apr. 24, 1917.

Application filed September 16, 1915. Serial No. 50,991.

To all whom it may concern:

Be it known that I, FRANK YOKEL, a citizen of the United States, residing at Pittsburgh, in the county of Allegheny and State 5 of Pennsylvania, have invented certain new and useful Improvements in Instantaneous Water-Heaters, of which the following is a specification.

My invention relates to instantaneous 10 water heaters.

Various structures have been produced for the purpose of providing rapid heating of the water, thus making it possible to obtain hot water immediately upon beginning 15 the operation of the device, but, so far as I am aware, these structures, where a capacity sufficient to be of material service is present, are of a complicated character and of comparatively high cost of manufacture. Consequently, the high cost of installation and maintenance tends to restrict the general use of this type of device, the cost generally being such as to restrict the use to users of considerable means. While 20 structures less costly have been produced, such reduction in cost has generally been at a sacrifice of efficiency, either by increasing the cost of operation, or materially reducing the efficiency.

30 In this connection, it is to be understood that inasmuch as these devices are generally operated by the combustion of gas, the possibility of loss of heat and the fact that the products of combustion are discharged into 35 the atmosphere surrounding the device, makes the question of the relative construction and arrangement of parts of material importance, these facts and capacity generally being the cause of the relatively high 40 cost of these devices.

The present invention aims to meet these conditions as to efficiency and capacity by a particular arrangement of parts in which these features are predominant and yet produced in such a manner as to render the device 45 low in cost, both of manufacture and operation, and therefore well within the means of the general public, thereby meeting a demand which heretofore could not 50 be met by reason of the comparatively high cost of manufacture and operation.

To these and other ends, the nature of which will be readily understood as the invention is hereinafter disclosed, the said in-

vention consists in the improved construction and combination of parts hereinafter fully described, illustrated in the accompanying drawing, and more particularly pointed out in the appended claims.

In the accompanying drawings, in which 60 similar reference characters indicate similar parts in each of the views,

Figure 1 is a side elevation of the complete device.

Fig. 2 is a vertical sectional view through 65 the same.

Fig. 3 is a detail sectional view of a fragmentary part of the device showing the manner in which the water passageways are produced.

70 Fig. 4 is a detail sectional view taken on line 4—4 of Fig. 2.

In the drawing, 10 designates the water inlet and 11 the gas inlet, these inlets being in the form of fittings connected respectively 75 to the general water and gas supplies. The fitting 11 is provided with a controlling member 11^a having an operating handle 11^b for controlling the gas supplied to the mixing chamber 12, the latter leading to the 80 burner as presently referred to.

The fitting 10 is provided with a controlling valve 10^a having a handle 10^b, the handles 10^b and 11^b being preferably connected together by a connection 13, thereby 85 enabling an operation of one handle to open or close both supplies. In addition, the fitting 10 is provided with a separate valve 10^c controlled by handle 10^d, this valve being adapted to vary the amount of water which 90 may be introduced when valves 10^a and 11^a are opened to their greatest extent. This supplemental valve 10^c therefore serves the purpose of practically controlling the temperature of the water discharged from the 95 device. Threaded to fitting 10 is a downwardly projecting pipe 14, the lower end of which is threaded to a fitting 15 having an arm 15^a and a pipe 15^b projecting outwardly, preferably from diametrically opposite sides 100 of the fitting, these parts being secured in suitable manner to the lower end of the coil-like structure 16 which forms the inner heating member of the water-circulating system of which pipe 14 may be considered 105 as the supply. The upper end of said member is connected, by pipe connection 17, with the upper end of another coil-like structure

18 which forms the outer heating member of the system, the lower end of the water passageway in the latter member being connected to a discharge pipe 19. The lower 5 end of member 18 has an outturned flange 18^a to which a skirt 20 is secured. This construction practically places the water supply and passageway through the heater as an individual unit, the parts being all connected together in such manner as to permit 10 of ready formation.

21 designates a casing surrounding member 18, this casing having its lower end mounted on flange 18^a, its upper end contacting with a spider 22 loosely mounted on pipe 14, said spider having the outer ends of its arms adapted to contact with a shoulder 23^a of a cap 23 also loosely mounted on pipe 14 above the casing or shell 21. The cap 23 20 and casing 21 are preferably held in fixed position by a nut 24 mounted on pipe 14 between the cap and fitting 10, this arrangement permitting the assemblage of the water heating unit and the casing independent of fitting 10, and enabling the unit to be readily 25 secured to the fitting without disturbing the relative arrangement of unit and casing. It will be understood, however, that the fitting 10 may be threaded directly into contact with cap 23 and thus position the parts 30 together. To provide the proper spacing of casing 21 at the upper end of member 18, the latter is preferably provided with a flange 18^b at its upper end.

35 Members 16 and 18 are substantial duplicates of each other excepting as to size, both being formed in a substantially similar manner. These members are each formed of two members *a* and *b* preferably conical. Member *a* is provided with a deep depression *a'* 40 extending spirally from top to bottom of the member, while member *b* is formed with a shallow depression *b'* arranged similarly. As both members are conical, they may be 45 assembled together by a threading action, the inner face of depression *a'* entering depression *b'*. After being assembled in this manner, a tool is preferably operated in the depression *a'* which has the effect of shaping 50 the walls of both depressions in a manner to prevent leakage between successive convolutions formed by the spiral arrangement of depressions, this connection being made without soldering, etc., the particular shape 55 of the members *a* and *b* being such as to aid in providing this result, the threading tending to bring the opposing surfaces into closer engagement.

60 As will be obvious, this form of constructing members *a* and *b* into the members or elements 16 and 18 not only provides for a highly efficient structure with a minimum amount of material, but in addition, the members can be completed at a comparatively small cost, and since the members *a* 65

and *b* are integral structures, their relative positions are maintained, while being individually strengthened by the corrugated effect produced by forming the depressions. Consequently, these members 16 and 18 are 70 of maximum strength and serviceability.

25 designates a burner of the Bunsen type, the burner having gas exit ports 25^a on the side and similar ports arranged annularly at the top, as shown in Fig. 2, the burner 75 being supported on a spider 26 secured to the skirt 20. The lower or extreme end of the burner is connected to the mixing chamber 12 by a pipe connection 27, the latter having a flange 27^a removably secured to the 80 spider 26, the latter having a projecting portion 26^a formed with an opening through which the outlet pipe 19 extends.

The burner 25 is preferably formed with a depressed portion 25^b forming a cup at 85 the top of the burner, the bottom of the cup having a threaded portion adapted to receive a threaded extension 15^c of fitting 15, this arrangement serving to accurately position the burner with respect to the inner 90 member 16. Since the outer member 18 is rigidly supported by the casing and inner member 16 by the casing and the burner (the latter being held rigid by the spider) 95 these members will be firmly held in position to maintain the spacing of the members constant, thereby eliminating liability of connection 17 being subjected to material strains. The burner thus acts as a positioning member for the water supply. The cup 100 105 25^b is adapted to receive any drippings or condensation, etc., which may come from the inner member 16,—the latter receiving cold water through connection 15^b—thus 110 localizing any production of condensation 105 in the apparatus within this member. Since such collection of condensation is in proximity to the upwardly flowing products, it will be understood that the cup may act 115 somewhat in the nature of a moistening 110 structure for the products. If desired, I may employ an overflow pipe 25^c within the cup, thereby limiting the amount of condensation which may be within the cup at any time, the overflow pipe discharging at any 115 desired point outside of the casing.

A pilot burner 28 is connected to the fitting 11 and extends into proper relation with burner 25.

As seen in Fig. 2, the flame from the 120 burner is located entirely above the lower plane of skirt 20, the burner also extending above the lower plane of the corrugated portion of member 18, the side openings 25^a 125 of the burner being directly opposite the lower convolutions of the spiral passageway at the exit end of said member 18. Consequently, the flame is not only protected from side drafts, but in addition has a major portion 130 in immediate proximity to that portion

of the circulating system adjacent the outlet for the water, thereby placing the maximum heat at that portion of the system where the water which has been preliminarily heated by the ascending heated products of combustion within the inner member and between the members 16 and 18 is in condition to be rapidly heated immediately before its discharge. As a result, the proper degree of temperature of the water can be obtained with a comparatively small burner, thus decreasing the consumption of gas in producing the desired result.

The water circulation is from fitting 10 through pipe 14 to fitting 15 and thence into the lower convolution of member 16, this being in proximity to the upper openings 25^a of the burner. The water then passes upwardly around the spiral passageway and into connection 17 where it begins its travel in the reverse direction through the spiral passageway of member 18 until it reaches the lower convolution and passes into the outlet 19. Consequently, the water is initially brought into proximity to the upper row of openings 25^a and is thus given a partial heat which is increased by the products of combustion which pass on opposite sides of member 16, reaching the top of the member where the extraction of heat units from the products has probably reached its maximum. The movement of the water in the outer member 18 is in the direction toward the maximum heat, so that the preliminary heating given in member 16 is continued and progressively increased toward the exit from the member 18.

By controlling the valve 10^c, a greater or less amount of water may be admitted without affecting the flame of the burner, thus controlling the passage of the water through the circulating system tending to regulate the temperature of the water discharged through outlet 19 by subjecting the water within the system to the action of the products for a greater or less amount of time.

By the use of connection 13, the main valves of the water and gas inlets are operated in unison from a single point, thus providing a unit control for both water and gas.

As will be understood, the assembling of the parts is readily had. The cap and casting are placed in position on the unit heretofore referred to and the parts secured to the fitting 10, after which the burner is placed in position by connecting stem 15^c with the threaded element within the cup, then positioning the spider 26 and securing it to the skirt, after which the gas connection between fitting 11 and the burner is secured in position through the means which secure flange 27^a to the spider 26.

When thus assembled, the structure is exceedingly rigid and is compact, (a structure

capable of serving the demands of a bathroom has the vertical length of the outer member 18 as approximately seven inches). In addition, the specific elements are of such a type as can be easily manufactured of materials which will withstand the severe conditions which this type of structures are required to meet.

While I have shown and described a preferred way in which the invention may be carried out, it will be readily understood that changes and modifications therein may be required or desired to meet the exigencies of use, and I desire to be understood as reserving the right to make any and all such changes as may be required or desired for such purposes in so far as the same may fall within the spirit and scope of the invention as expressed in the accompanying claims.

What I claim is:—

1. In a device of the character described, a water-circulating system having a controllable inlet and an outlet, said system including an annular spiral passageway leading to the outlet, and a controllable burner extending above the bottom plane of and positioned in direct opposition to more than a single convolution of the outlet portion of said spiral passageway, whereby the water will be subjected to its maximum heating action immediately in advance of its discharge from the system, said burner and the water supply for the passageway being connected together, whereby the burner acts as a positioning member for the supply connections.

2. In a device of the character described, a water-circulating system having a controllable inlet and a permanently-open outlet, said system including an annular spiral passageway leading to the outlet, and a controllable burner extending above the bottom plane of and positioned in direct opposition to more than a single convolution of the outlet portion of said spiral passageway, whereby the water will be subjected to its maximum heating action immediately in advance of its discharge from the system, said burner and the water supply for the passageway being connected together, whereby the burner acts as a positioning member for the supply connections.

3. In a device of the character described, a water-circulating system having a controllable inlet and an outlet, said system including an outer and inner member each having a spiral water passageway, said members being connected to join the passageways, a water supply leading to said inner member, the outer member extending below the inner member and carrying the outlet, and a controllable burner extending above the bottom plane of and positioned in direct opposition to more than a single convolution of the passageway leading immediately to

the outlet, and also in juxtaposition to the inlet end of the spiral passageway of the inner member.

4. In a device of the character described, 5 a water-circulating system having a controllable inlet and an outlet, said system including an annular spiral passageway leading to the outlet, and a controllable burner positioned in direct opposition to 10 more than a single convolution of the outlet portion of said spiral passageway, and means within the system for independently controlling the flow of water therethrough, said means remaining unaffected by the results of controllable inlet manipulation.

5. In a device of the character described, 20 a water-circulating system having a controllable inlet and an outlet, said system including an annular spiral passageway leading to the outlet, and a controllable burner positioned in direct opposition to more than a single convolution of the outlet portion of said spiral passageway, and means within the system for independently controlling the 25 flow of water therethrough, said means being positioned in juxtaposition to the controllable inlet, said means remaining unaffected by the results of controllable inlet manipulation.

30 6. In a device of the character described, a water-circulating system having a controllable inlet and an outlet, said system including an annular spiral passageway leading to the outlet, and a controllable burner 35 positioned in direct opposition to more than a single convolution of the outlet portion of said spiral passageway, said system including a supply pipe directly connected to and forming a support for the burner, said 40 burner acting as a positioning member for the supply pipe.

7. In a device of the character described, 45 a water-circulating system having a controllable inlet and an outlet, said system including an annular spiral passageway leading to the outlet, and a controllable burner positioned in direct opposition to more than a single convolution of the outlet portion of said spiral passageway, said system including 50 a supply pipe, and threaded means directly connecting the supply pipe and burner, whereby the latter is removably supported by the supply pipe, said burner acting as a positioning member for the supply 55 pipe.

8. In a device of the character described, 60 a water-circulating system having a controllable inlet and an outlet, said system including an annular spiral passageway leading to the outlet, said system also including a supply pipe, a burner directly supported by said pipe in direct opposition to more than a single convolution of said passageway adjacent the outlet, said burner acting 65 as a positioning member for the supply pipe

and a controllable gas inlet leading to said burner.

9. In a device of the character described, 70 a water-circulating system having a controllable inlet and an outlet, said system including an annular spiral passageway leading to the outlet, said system also including a supply pipe, a burner supported by said pipe in direct opposition to more than a single convolution of said passageway adjacent 75 the outlet, an annular skirt depending from said system, a spider carried by the skirt, and a controllable gas inlet leading to said burner and secured to said spider.

10. In a device of the character described, 80 a water-circulating system having a controllable inlet and an outlet, said system including an annular spiral passageway leading to the outlet, said system including a supply pipe, a burner supported by said 85 pipe in direct opposition to more than a single convolution of said passageway adjacent the outlet, said burner acting as a positioning member for the supply pipe, and a controllable gas inlet leading to said 90 burner, said controllable gas and water inlets being located at opposite ends of the device, and means for connecting the inlet controls to provide movements thereof in unison. 95

11. In a device of the character described, 100 a water-circulating system having a controllable inlet and an outlet, said system including a pair of annular members each having a spiral water passageway, said members being connected to join the passageways, a water supply leading to one of said members, the other member carrying the outlet, said outer member having a depending skirt, a casing surrounding said outer member, a cap above said members and casing, a burner supported by the supply tube and extending above the bottom plane of the 105 passageway of the outer member, a spider carried by said skirt, and a controllable gas inlet leading to the burner and secured to said spider. 110

12. In a device of the character described, 115 a water-circulating system unit comprising a pair of conical-shaped concentrically-arranged members connected at their upper ends by a passageway, said members each having a spirally arranged water passageway, a water supply extending axially through and connected to the inner member 120 of the unit, and a water outlet connected to a spiral convolution of the outer member.

13. In a device of the character described, 125 a water-circulating system unit comprising a pair of conical-shaped concentrically-arranged members connected at their upper ends by a passageway, said members each having a relatively-narrow spirally-arranged water passageway, a water supply extending axially through and connected to 130

the inner member of the unit, and a water outlet connected to a spiral convolution of the outer member.

14. In a device of the character described, 5 a water-circulating system unit comprising a pair of conical-shaped concentrically-arranged members connected at their upper ends by a passageway, said members each having a spirally-arranged water passage- 10 way, a water supply extending axially through and connected to the inner member of the unit, and a water outlet connected to a spiral convolution of the outer member, said supply having a controllable inlet, said 15 outlet being permanently open.

15. In a device of the character described, a water-circulating system unit comprising a pair of conical-shaped concentrically-arranged members connected at their upper 20 ends by a passageway, said members each having a spirally-arranged water passageway, a water supply extending through and connected to the inner member of the unit, and a water outlet connected to a spiral con- 25 volution of the outer member, said supply having a controllable inlet, said outlet being permanently open, and means between the controllable inlet and the inner member for independently controlling the flow of water 30 therethrough, said means remaining unaffected by the results of controllable inlet manipulation.

16. In a device of the character described, a water-circulating system having an ele- 35 ment comprising a pair of conical-shaped members each having inwardly-extending depressions arranged spirally from one end to the other of the conical-shaped portions, the depressions of the inner member being 40 of less depth than those of the outer member, the walls of said depressions being complemental to permit a threading action there- between in assembling the members.

17. In a device of the character described,

a water-circulating system having an ele- 45 ment comprising a pair of conical-shaped members each having inwardly-extending depressions arranged spirally from one end to the other of the conical-shaped portions, the depressions of the inner member being 50 of less depth than those of the outer member, the walls of said depressions being complemental to permit a threading action therebetween in assembling the members, the depth of the depressions of the outer 55 member being sufficient to form a spiral water passageway between the members with the inner member providing the inner wall of the passageway.

18. In a device of the character described, 60 a water-circulating system having a controllable inlet and an outlet, said system including an annular spiral passageway leading to the outlet, a supply pipe within the system, a burner supported directly by said 65 pipe and extending above the bottom plane of the passageway, said burner having a cup-shaped depression to receive condensation from the system, and a controllable gas inlet for said burner. 70

19. In a device of the character described, a water-circulating system having a controllable inlet and an outlet, said system including an annular spiral passageway leading to the outlet, a supply pipe within the 75 system, a burner supported directly by said pipe and extending above the bottom plane of the passageway, said burner having a cup-shaped depression to receive condensation from the system, an overflow pipe for 80 said burner depression, and a controllable gas inlet for said burner.

In testimony whereof I affix my signature in presence of two witnesses.

FRANK YOKEL.
